HENRY S. HALE, OF PHILADELPHIA, PENNSYLVANIA, ASSIGNOR TO THE
HALE AND KILBURN MANUFACTURING COMPANY, OF PHILADELPHIA,
PENNSYLVANIA, A CORPORATION OF PENNSYLVANIA.

CUSHION.

No. 825,826.

Specification of Letters Patent.

Patented July 10, 1906.

Application filed May 10, 1905. Serial No. 259,776.

To all whom it may concern:

Be it known that I, HENRY S. HALE, a citizen of the United States, residing at Philadelphia, in the county of Philadelphia and State of Pennsylvania, have invented certain new and useful Improvements in Cushions, of which the following is a specification.

The present invention relates to cushions generally, but is particularly applicable to cushions of the type commonly employed in connection with car-seating.

In the bank-cushions commonly in use it is customary to provide a head-roll adjacent to one or both of the upper and lower edges thereof in order to furnish adequate and comfortable support for the occupant of the seat. Where the seat is of the "turnover" variety in which the same surface is used in either facing direction for the support of the occupant, such head-roll has been arranged adjacent to each of the upper and lower edges, while in the case of a back of the "walk-over" type, wherein one or the other side is presented according to the facing direction of the seat, a head-roll on each side, but adjacent to the upper surface only, is provided. In the manufacture of these back-cushions heretofore it has been customary to form the head-roll by laboriously stitching the material which overlies the upholstery to a part lying below it in order to form a suitable angle marking the boundary of the head-roll. This has proved both time-consuming and expensive, and in addition it has been difficult to give this portion of the cushion a uniform and finished appearance.

The object of the present invention is both to improve the appearance of the cushion and to greatly simplify and cheapen the manufacture thereof, and this is accomplished by avoiding the laborious stitching above referred to, forming the proper angle and giving the cushion the proper contour by the use of a steel rod or bar or equivalent device secured in suitable manner to one of the layers of textile fabric and coacting with the frame. Such rod, bar, or similar device may be readily combined either with loops or other appurtenances of such textile fabric and secured at either end to the frame of the cushion, giving thereby a firm and uniform appearance to the cushion-frame and adapting

it to receive the plush or other covering with which the cushion may be finished.

In the accompanying drawings, Figure 1 is a face view of a car-seat-back cushion of the turn-over type, certain portions of the fabric and upholstery being removed. Fig. 2 is an outline edge view of a seat-cushion of the walk-over type, to which the invention may be applied with equal advantage. Fig. 3 is a cross-section of the cushion shown in Fig. 1, and Figs. 4 and 5 are detail views hereinafter referred to.

Referring to the drawings, in which similar letters denote corresponding parts, it will be seen that the cushion-frame includes the end members a a' and the longitudinal side members a^2 a^3 , the end members a a' being substantially higher than the members a^2 a^3 . Extending between and secured at their ends to the side members a^2 a^3 is a series of cross-bars a^4 , each supporting a transverse series of coil-springs a^5 . A similar but longitudinal series of coil-springs a^6 is mounted upon each of the side members a^2 a^3 of the frame to form the head-roll.

The upper ends of the coil-springs a^5 of each transverse series are secured to a transverse band B of corrugated steel, and over this extends a band b of webbing, the object whereof is to prevent said band B from cutting through the overlying material b' , known as the "first canvas." The first canvas b' may be either continuous, so as to overlie both the body of the cushion, as well as the head-rolls, or it may be in two parts, the portion b' overlying the body of the cushion and secured at its lateral edges to any suitable part—as, for instance, the side members a^2 a^3 —and two adjacent portions b^3 overlying the longitudinal coil-spring systems upon the side members a^2 a^3 of the frame, the edges of such portions b^3 being tacked or otherwise secured to the edges of said side members a^2 a^3 . The upper ends of each of the longitudinal series of coil-springs a^6 are secured to a longitudinal band b^2 of corrugated steel.

C designates the inner cover of the cushion-frame, and this may be made of muslin or other suitable material. Heretofore it has been the practice to secure this at each side edge of the seat-frame, and in addition

to stitch the same adjacent to the junctions between the body portion of the cushion and the head roll or rolls thereof. In the present invention the necessity for this stitching is entirely obviated in the following manner: The muslin cover C is provided at each meeting-point between the body of the cushion and a head-roll with a loop e, which may readily be made by simply folding the material and then stitching it along a line parallel with the fold. The muslin cover is then laid upon the seat-frame over the upholstery D, which overlies the coil-spring system both of the body portion of the cushion and of the head roll or rolls thereof, and through each loop is run a steel rod or bar e', the ends whereof are secured in suitable orifices e² in the end members a a' of the frame. After the rods or bars have been so positioned they may be secured in any suitable manner—as, for instance, by a tack through the members a a', closing such orifices e². This draws the loops e of the inner cover C uniformly down into the angle between the body portion and the head-rolls of the cushion, and, if desired, each rod may be secured intermediate of its length to an adjacent but underlying part of the structure—as, for instance, to the first canvas, as indicated at e³, Fig. 5. The extreme (side) edges of the inner cover may then be tacked or otherwise secured either to the extreme edges or under sides of the side members a² a³, thus confining in position the upholstery D, giving the cushion-frame as a whole the proper outline or contour and adapting it to receive the cover, by which it may be finished for use.

In applying the back-cover I prefer to use a thin layer F of raw cotton or similar material, held in place by a sheet f of textile material, such as muslin, over which may be placed the cover f' of plush or other similar material. The edges of both the muslin f and cover f' may be tacked or otherwise secured to the outer edges of the side members a² a³, as well as of the end members a a'. The face-cover f² of the cushion, which may also be of plush or other suitable material, may be laid directly upon the muslin layer C, and its edges also tacked or otherwise secured, preferably, over the edges of the plush cover f', the point at which both the back and face covers are secured to the side and end members of the frame being covered by the beading or braid of metal or textile material f³, giving the cushion a finished appearance at its edges.

It will thus be seen that I avoid the laborious stitching of the muslin cover C to the first canvas b and that the operation of securing the muslin cover in position is very simple and quickly performed, involving, as it does, only the introduction of the rods e' through their respective loops and the securing of the ends of such rods in the end mem-

bers a a' of the cushion-frame. The securing of the rods e' to the first canvas is not absolutely essential, but is suggested as a simple way of maintaining such rods in position as against their tendency to bend or bow outwardly under the strain of the muslin cover and the upholstery and spring systems underlying the same.

By illustrating and describing the rods or bars e' and the coacting loops e (or equivalent devices) in connection with the inner cover C of the cushion I do not wish to be understood as confining myself thereto, as it is obvious that the loops or equivalent devices may be formed in the outer or back cover for coaction with such rods or bars e', or, if desired, the loop and rod construction may be employed in connection with both such inner and outer covers.

Having now described my invention, what I claim as new therein, and desire to secure by Letters Patent, is as follows:

1. In a cushion, the combination with a frame, of a sheet of flexible material provided with a loop, operative portions of said sheet extending on either side of said loop, means for yieldingly pressing said portions outward from said frame, and a rod or bar coacting with said loop and with said frame, substantially as set forth.

2. In a cushion, the combination with a frame, of a sheet of flexible material provided with a loop intermediate its edges, means for yieldingly pressing outward from said frame the portions of said sheet lying on either side of said loop, a rod or bar coacting with said loop and at its ends with said frame, and means for securing said rod or bar intermediate of such ends, substantially as set forth.

3. In a cushion, the combination with a frame comprising side and end members, of a plurality of springs secured thereon, upholstery material supported by said springs, a sheet of flexible material overlying said upholstery material and secured to said frame, said sheet having a loop formed therein, and a rod or bar coacting with said loop and said frame, substantially as set forth.

4. In a cushion, the combination with a frame having a body portion and a head-roll, of coil-springs forming part of said body portion and said head-roll, spring-bands overlying said coil-springs, a first canvas overlying said coil-springs and secured to said frame, a covering sheet of flexible material, and means coacting with said sheet and with said frame, independently of said first canvas, for maintaining said sheet in position, substantially as set forth.

5. In a cushion, the combination with a frame, an upholstery device and springs supporting said device upon said frame, of a sheet of flexible material overlying said device and provided with a loop, a rod or bar coacting with said loop, and means carried

by said frame for securing the ends of such rod or bar, substantially as set forth.

6. In a cushion, the combination with a frame comprising side and end members, of a series of coil-springs arranged in longitudinal series over said side members and in transverse series over the body portion of said frame intermediate of said side members, a series of steel bands overlying said coil-spring, means for placing said bands and coil-springs under tension, a sheet of flexible material secured at its edges to said frame and provided with a loop, and a rod or bar coacting with said loop and with said frame, substantially as set forth.

7. In a cushion, the combination with a frame, including coil-springs, overlying me-

tallic bands, and a first canvas extending over said bands and coil-springs and secured at its edges to said frame, of upholstery material overlying said first canvas, a flexible cover overlying said upholstery material, said cover being provided with a loop for coaction with a rod or bar secured at its ends to said frame, and a finishing cover for said cushion extending over said flexible cover and secured to said frame, substantially as set forth.

This specification signed and witnessed this 28th day of April, 1905.

HENRY S. HALE.
